RAILWAY TRAFFIC CONTROLLING
APPARATUS

Willard P. Place, Wilkinsburg, Pa., assignor to
The Union Switch & Signal Company, Swiss-
vale, Pa., a corporation of Pennsylvania

Original application August 3, 1938, Serial No.
222,883. Divided and this application October
7, 1939, Serial No. 298,435

10 Claims. (Cl. 246—63)

My invention relates to railway traffic controlling apparatus, and particularly to apparatus for railway cab signal systems.

The present application is a division of my co-pending application Serial No. 222,883, filed August 3, 1938, for Signal systems.

I shall describe several forms of apparatus embodying my invention, and shall then point out the novel features thereof in claims.

10 Railway cab signal systems using track circuits supplied with coded alternating current are in general use. Alternating current of a convenient frequency such as 100 cycles per second is periodically interrupted at different code rates 15 or frequencies according to different traffic conditions, the code rates of 180, 120 and 75 being generally used to reflect clear, approach restricting and approach traffic conditions, respectively. Energy is received by a train carried circuit 20 coupled with the track circuit and such energy is used to govern a cab signal through decoding apparatus selectively responsive to these different code rates or frequencies. Such decoding apparatus has been standardized in construction for 25 the present day cab signal systems.

Railway cab signal systems using track circuits supplied with coded direct current have been proposed. Time spaced impulses of direct current of a preselected polarity are supplied to 20 a track circuit at different code rates according to different traffic conditions in advance of the track circuit, and the code rates of 180, 120 and 75 may be employed the same as in systems using coded alternating current. The individual 25 impulses of direct current are preferably of relatively high peak voltage and of short duration. The high peak voltage serves as an aid to the shunting sensitivity of the track circuit and the short duration serves to limit the energy 30 output from the current source, which is ordinarily a battery, to a low energy level. Energy is received on the train by a train carried circuit coupled with the track circuit and such energy is used to govern a cab signal through decoding 35 apparatus which preferably is of the standard construction.

A railway having certain divisions already equipped with track circuits using coded alternating current may find it desirable to equip other 40 divisions with track circuits using coded direct current and to operate locomotives provided with cab signals over either division. That is to say, a railway may wish to use a locomotive equipped with cab signals either with a territory having 45 coded alternating current track circuits or with a territory having coded direct current track circuits, the cab signals being controlled by both forms of track circuits. It becomes necessary to equip such locomotive with train carried receiving apparatus that controls a cab signal in 50

response to energy received from either a track circuit supplied with coded alternating current or from a track circuit supplied with coded direct current.

Accordingly, a feature of my present invention 5 is the provision of novel and improved receiving apparatus for cab signal systems which apparatus can be used either with coded alternating current or with coded direct current. Again, a feature of my invention is the provision of receiving apparatus of the type here involved having automatic switching means for selectively rendering active one or the other of two receiving channels operating in parallel, one of such receiving channels being selectively responsive to 10 code impulses of direct current and the other of such receiving channels being selectively responsive to coded alternating current. Other features and advantages of my invention will 15 appear as the specification progresses.

In the accompanying drawings, Fig. 1 is a 20 diagrammatic view showing one form of track-way apparatus embodying my invention when applied to a four indication signaling system for railways. Figs. 2, 3 and 4 are diagrammatic 25 views showing three different forms of train carried apparatus each embodying my invention when applied to a four indication cab signaling system.

In each of the several views similar parts are 30 designated by similar reference characters.

Referring to Fig. 1, the track rails 1a and 1b of a stretch of railway track are formed into consecutive insulated track sections of which only one full section W—X and the adjoining 35 ends of the two adjacent sections are shown for the sake of simplicity. Each track section is provided with a track circuit comprising the track rails, means for supplying code impulses of direct current connected across the rails at the exit end of the section, and a code responsive relay means connected across the rails at the entrance end of the section. Thus the source of current impulses for the track circuit for the section W—X and the code responsive relay 40 45 means for the track circuit for the section to the left as viewed in Fig. 1, that is, the track circuit next in advance of section W—X, are located adjacent the junction W of these two track sections. The means for supplying such code impulses of direct current to a track circuit is governed by the code responsive relay means for the track circuit for the section in advance according to different traffic conditions in advance.

The source of code impulses of direct current for the track circuit for the section W—X comprises a battery 2, a track transformer T1 and a code transmitter CT2. A portion of a winding 4 50 55 60 of transformer T1 is connected across the rails

adjacent the exit end W of section W—X. The full winding 4 of transformer T1 is connected with battery 2 over contacts of the code transmitter CT2 in accordance with traffic conditions in advance. The code transmitter CT2 is preferably of the frequency code type, several of such types being well known to the art. The operating winding of code transmitter CT2 is connected with a convenient source of current 10 and is continuously active to operate three code contact members 75b, 120b and 180b, the arrangement being such that the code contact member 75b is operated to close contact 75a—75b at the rate of say 75 times per minute, code contact member 120b is operated to close contact 120a—120b at the rate of 120 times per minute and the code contact member 180b is operated to close contact 180a—180b at the rate of 180 times per minute. 15

At such time as a relay WA of the code responsive relay means to be later referred to for the track circuit of the section next in advance of section W—X is picked up closing front contact 143, or when relay WA is released closing back contact 144 and a second relay WR of the code responsive relay means is picked up closing front contact 145, the battery 2 is connected across the winding 4 of transformer T1 over contact 180a—180b of the code transmitter CT2 20 and direct current impulses of the code rate or frequency of 180 per minute are supplied to the track circuit for section W—X, the polarity of the code impulses of current being all the same, for example, they may be all of positive polarity. 25

When both relays WA and WR are released closing back contacts 144 and 146, respectively, and a third relay WL of the code responsive relay means is picked up closing front contact 147, the battery 2 is connected across winding 4 over contact 120a—120b of the code transmitter CT2 30 and direct current impulses of the code rate or frequency of 120 impulses per minute are supplied to the track circuit of section W—X, the impulses being all of positive polarity. Again, 35 when relays WA, WR and WL are all released closing back contacts 144, 146 and 148, respectively, battery 2 is connected across winding 4 over contact 75a—75b of the code transmitter and the track circuit for section W—X is supplied with impulses of direct current at the code rate or frequency of 75 impulses per minute, the impulses being all of positive polarity. 40

The code responsive relay means for the track circuit of section W—X includes a code following relay XTR1 connected across the rails at the entrance end of the section. Code following relay XTR1 is effectively energized and picked up by each impulse of direct current supplied to the track circuit and hence relay XTR1 operates its contact member 149 at the code rate or frequency of the impulses supplied to the track circuit. Operation of the code contact member 149 causes direct current to be alternately supplied to the two portions of primary winding 150 of a transformer T8 with the result that electromotive force of a frequency corresponding to the rate at which contact member 149 is operated is induced in the secondary winding 151 of that transformer and is applied to the input terminals of a frequency decoding unit XFD. The specific structure of the frequency decoding unit XFD is immaterial, several of such decoding units being well known. Preferably the structure of the decoding unit XFD would be that of standard construction. It is deemed sufficient for this appli-

cation to say that the decoding unit XFD causes a relay XA connected with its output side to be energized and picked up only in response to current impulses corresponding to relay XTR1 operated at the 180 code rate, causes a relay XR connected with its output side to be energized and picked up only in response to current impulses corresponding to relay XTR1 operated at the 120 code rate, and causes a relay XL connected with its output side to be energized and picked up in response to relay XTR1 operated at either the 180, 120 or 75 code rate. 5

In like fashion a code following relay WTR1 for the track circuit of the section next in advance of section W—X governs through a transformer T9 a frequency decoding unit WFD for selectively energizing the relays WA, WR and WL in accordance with the code rate of the impulses of the track circuit current of that section. 15

It should be pointed out that the code rate of 20 180 impulses per minute for a track circuit represents clear traffic conditions, the code rate of 120 impulses per minute for the track circuit represents approach restricting traffic conditions, the code rate of 75 impulses per minute for the 25 track circuit represents approach traffic conditions, and the absence of any of these code impulses represents stop or slow speed traffic conditions.

The relays WA, WR and WL govern the operating circuits for a wayside signal WS which governs traffic through the track section next in advance of section W—X. These operating circuits for signal WS are shown conventionally only in Fig. 1 for the sake of simplicity, since 35 they would be in accordance with standard practice and form no part of my present invention.

The relays XA, XR and XL for the track circuit of section W—X govern the track circuit for the section next in the rear and the operating 40 circuits for a wayside signal XS in the same manner as the relays WA, WR and WL control the track circuit of section W—X and the operating circuits for signal WS.

It should be pointed out that the code impulses of direct current applied to the track circuits of section W—X are of relatively short duration and relatively high peak voltage as explained fully in my copending application Serial No. 222,883. 45

The track circuit of each track section of the stretch of railway of which section W—X forms a part would be provided with trackway apparatus the same as described for the track circuit of section W—X. 55

Another stretch of the railway would be arranged into consecutive track sections each of which is provided with trackway apparatus operating to supply to the track circuits coded alternating current. The alternating current would 60 preferably be periodically interrupted or coded at the code rate or frequency of 180, 120 and 75 impulses per minute according to clear, approach restricting and approach traffic conditions in advance. Trackway apparatus operative to supply such coded alternating current is well known and in widespread use and may be that disclosed in the United States Letters Patent No. 1,773,515, granted August 19, 1930 to Charles C. Buchanan, for Railway traffic controlling apparatus. 65

Referring to Fig. 2, the train carried apparatus includes an inductor or receiving circuit comprising two windings 25 and 26 mounted on the train in inductive relation with the track rails 1a 70 75

and 1b, respectively. The connections of windings 25 and 26 are preferably such that the electromotive forces induced therein by current flowing in opposite directions in the rails 1a and 1b at any given instant add their effects.

The train carried apparatus of Fig. 2 is provided also with two receiving channels one effectively influenced by recurrent impulses of direct current and the other effectively influenced by coded alternating current. If the train on which the apparatus of Fig. 2 is mounted is operating over territory where the track circuits are supplied with coded direct current impulses such as provided by the trackway apparatus of Fig. 1, a receiving channel including a controlled ionization type of electron tube is responsive thereto. When the train is operating over territory where the track circuits are supplied with coded alternating current of 100 cycles per second such as is widely used in present day cab signaling systems and such as provided by trackway apparatus shown in the aforementioned United States Letters Patent No. 1,773,515, a receiving channel including a high vacuum amplifying electron tube is responsive thereto.

In Fig. 2, the receiving channel responsive to direct current impulses includes an input transformer T12, a controlled ionization tube G3 and a master code following relay MR1. The receiving channel responsive to coded alternating current includes an input transformer T13, a high vacuum pentode tube 25L6 and a master code following relay MR. The inductor windings 25 and 26 are connected with the primary windings 172 and 173 of the transformers T12 and T13, respectively, in multiple. Hence energy received from the track circuit is applied to the two receiving channels in parallel.

Referring to the receiving channel responsive to impulses of direct current, the controlled ionization tube G3 is of the indirect heater type, the two principal electrodes being anode 164 and cathode 165, and its control element being a grid 166. The grid circuit for tube G3 is connected with a secondary winding 175 of the input transformer T12 as will be apparent by an inspection of Fig. 2. A generator 84 of a motor generator MG serves as the source of electromotive force for the anode circuit of tube G3, the motor 85 of the motor generator MG being supplied with current from any convenient source such as a headlight generator (not shown) whose terminals are B32 and N32. The generator 84 whose terminals are designated B300 and N300 would, for example, supply a voltage of say 300 volts.

The anode circuit for tube G3 includes terminal B300 of generator 84, a resistor 32, top winding of code following master relay MR1, anode 164, tube space to cathode 165 and terminal N300 of the generator. A condenser C1 and an inductor L1 are connected with this anode circuit to provide the tube G3 with an oscillatory circuit, this oscillatory circuit extending from condenser C1 over inductor L1, top winding of relay MR1, the anode-cathode space of tube G3 and back to condenser C1. Normally the voltage applied by generator 84 is ineffective to render the tube G3 conducting and hence the condenser C1 is normally charged at substantially the voltage of generator 84. The relay MR1 when operated causes through its contact member 169 direct current to be alternately supplied to the two portions of winding 168 of a transformer

T11 over a circuit to be later traced, with the result that electromotive forces are induced in secondary winding 167 of transformer T11 and current impulses of a rate corresponding to the rate at which relay MR1 is operated are supplied to the input terminals of a frequency decoding unit TFD. A resistor 197 is preferably connected across the supply circuit ahead of the contact member 169 to allow a substantially uniform flow of direct current through the winding 168 when relay MR1 is not operated. A further purpose of resistor 197 will appear hereinafter.

The frequency decoding unit TFD would preferably be of standard construction and relays TA, TR and TL connected with the output side of the decoding unit TFD are selectively energized according to the code rate of the impulses of current supplied to the decoding unit, the arrangement being that relay TA is energized and picked up when and only when the relay MR1 is operated at the code rate of 180, relay TR is energized and picked up when and only when relay MR1 is operated at the code rate of 120 and relay TL is energized when relay MR1 is operated at either the 180, 120 or 75 code rate. The relays TA, TR and TL are used to govern the operating circuits for a cab signal CS1 as is obvious from Fig. 2.

Referring now to the receiving channel responsive to coded alternating current and which channel includes tube 25L6, a condenser 174 is interposed in the connection of primary winding 173 of transformer T13 with the windings 25 and 26, and a condenser 184 is connected across the secondary winding 176 of transformer T13 which secondary winding is included in the grid circuit of tube 25L6 as is apparent from Fig. 2. The parts are so proportioned that transformer T13 and condensers 174 and 184 form a filter interposed between windings 25 and 26 and the control element of tube 25L6 and which filter is tuned sharply to pass only the frequency of the alternating current, that is, the filter is tuned to resonance at the frequency of 100 cycles per second.

The electron tube 25L6 is of the low voltage type and its plate circuit is supplied from the B32-N32 source of current, plate 177 of tube 25L6 being connected with terminal B32 through primary winding 178 of a transformer T14, and cathode 179 of the tube being connected with terminal N32 through a biasing resistor 198. The secondary winding 181 of transformer T14 is connected with the winding of code following relay MR. Code following relay MR is of the usual code following type and is provided with two contact members 182 and 183 which remain in the position to which they were last moved when the relay is deenergized. Relay MR controls the supply of direct current to winding 168 of transformer T11 in a manner to shortly appear and hence when operated causes impulses of current to be supplied to the input side of decoding unit TFD which impulses are of a rate corresponding to the rate at which relay MR is operated. It follows that alternating current of the code rates of 180, 120 and 75 when applied to the receiving channel including tube 25L6 is amplified and decoded to control relays TA, TR and TL and in turn to control cab signal CS1 in accordance with the code rate.

Assuming the train on which the apparatus of Fig. 2 is mounted is moving over the track section V-X of Fig. 1 under clear traffic conditions so that direct current impulses of 180 code

rate are supplied to the track circuit, corresponding electromotive forces are induced in the windings 25 and 26 and are applied to the two receiving channels in parallel. Since the wave 5 form of the electromotive force induced in windings 25 and 26 in response to the direct current impulses contain little if any alternating current energy of 100 cycles, the filter comprising the transformer T13 and condensers 174 and 184 10 substantially blocks all such energy from tube 25L6 and the receiving channel including tube 25L6 is not affected by such current impulses. The windings of transformer T12 are so connected that the first half cycle of the electromotive force induced in the secondary winding 175 of transformer T12 in response to a track circuit impulse of direct current of positive polarity causes the grid 166 of tube G3 to be 15 positive in potential with respect to the cathode 165 and tube G3 is ionized and becomes conductive. Current flows from condenser C1 through inductor L1, top winding of relay MR1, anode-cathode space of tube G3, and back to condenser C1. Current also flows from generator 84 20 through the associated anode circuit including resistor 32 and the top winding of relay MR1 as well as the anode-cathode space of tube G3. Because of the oscillatory nature of the discharge from the condenser C1, the current through tube 25 G3 falls after a first surge to a relatively low value and the tube G3 deionizes and becomes nonconducting. The condenser C1 is quickly 30 recharged and the above described operation is repeated for each code impulse of direct current of the track circuit, and relay MR1 is operated at the code rate of 180. It should be observed that the negative half cycle of the induced electromotive force does not affect ionization of tube G3.

40 Relay MR1 when thus operated causes direct current to be alternately supplied to the two portions of primary winding 168 of transformer T11 over a signaling or supply circuit which can be traced from terminal B over contact member 45 183 of relay MR in its right-hand position, primary winding 185 of a transformer T15 to be referred to, left-hand portion of winding 168 of transformer T11 and back contact of contact member 169 of relay MR1 or right-hand portion of winding 168 and front contact of contact member 169, contact member 182 of relay MR in its right-hand position and to terminal C. It follows that current impulses of a rate corresponding to the 180 code rate are supplied to 50 the decoding unit TFD and relay TA in turn is effectively energized and picked up to cause signal CS1 to display a clear indication.

Since the impulses passed by tube G3 are relatively short and since it is desirable that code 55 impulses supplied to the decoding unit TFD have nearly equal "on" and "off" periods, the relay MR1 is provided with a lower winding which is connected with a reactor L3 over front contact 196. When relay MR1 is released ("off" 60 position) reactor L3 is supplied with current from the source B32—N32 over back contact 195 and reactor L3 stores up magnetic energy, the amount of energy depending within limits upon the length of time reactor L3 is supplied with 65 current. When relay MR1 is picked up ("on" position) the reactor L3 is connected with the lower winding of relay MR1 and disconnected from the current source. This causes current to flow in the lower winding of relay MR1 due to 70 the decay of the magnetic energy stored in re-

actor L3 and relay MR1 is maintained energized for an interval subsequent to the termination of the impulse of current flowing in the top winding of that relay due to the action of tube G3. Thus the current impulses supplied to decoding unit 75 TFD due to the operation of relay MR1 have substantially equal on and off periods.

Operation of the apparatus in response to direct current impulses supplied to the track circuit of section W—X of the 120 or 75 code 10 rate in accordance with different traffic conditions causes relay MR1 to be operated at a corresponding code rate and relays TR and TL to be picked up at the 120 code rate and relay TL only picked up at the 75 code rate so that 15 cab signal CS1 is caused to display an approach restricting indication or an approach indication according to the traffic condition.

It should be noted that the transformer T15 is so designed and proportioned that when the 20 relay MR1 is operated in the manner explained above, the electromotive forces induced in the secondary winding 186 when rectified by a full wave rectifier 187 are not effective to energize a relay R6 whose winding is connected across 25 the output terminals of rectifier 187 sufficiently to pick up that relay. Furthermore, the resistor 197 which allows a substantially uniform amount of direct current to flow when relay MR1 is operated aids in assuring that not sufficient 30 energy is supplied to relay R6 to pick up that relay.

Assuming the train on which the apparatus of Fig. 2 is mounted is operating over a track circuit to which coded alternating current is 35 supplied by trackway apparatus of the aforementioned United States Letters Patent No. 1,773,515 at the code rate of 180, 120 or 75 according to different traffic conditions, each "on" period of the alternating current induces an 40 electromotive force in the windings 25 and 26 which has a frequency of 100 cycles per second and is passed by the filter including transformer T13 and condensers 174 and 184 to the grid circuit of tube 25L6. The electromotive force now 45 induced in windings 25 and 26 and thus applied to the grid circuit of tube 25L6 is amplified and applied through transformer T14 to master relay MR to operate relay MR in the well-known manner. Code following relay MR when thus 50 operated causes current from the source B—C to be reversibly supplied to the left-hand portion of winding 168 of transformer T11 over the previously traced supply circuit with the result that 55 electromotive forces are induced in the secondary winding 167 of transformer T11 and impulses of current of a corresponding rate are applied to the decoding unit TFD so that relays TA, TR and TL are selectively controlled according to the code rate at which relay MR is operated and signal CS1 displays an indication corresponding to the code rate of the alternating current supplied to the track circuit.

When relay MR is operated, the direct current flowing in primary winding 185 of transformer 65 T15 is periodically reversed and the electromotive force induced in secondary winding 186 of that transformer when rectified by rectifier 187 is of sufficient magnitude to effectively energize relay R6 to pick up that relay, relay R6 being retained 70 picked up from one impulse of the track circuit current to the next due to its slow releasing characteristic. Relay R6 in picking up opens its back contact 188 and removes current from motor 85 of the motor generator MG so that gen- 75

erator 84 no longer supplies current to the anode circuit of tube G3, with the result that the receiving channel including tube G3 is desensitized. That is, relay R6 is operated by the receiving channel responsive to coded alternating current and automatically switches the receiving channel responsive to direct current impulses to an inactive condition.

In Fig. 3, the train carried apparatus comprises two receiving channels the same as in Fig. 2. In Fig. 3, the controlled ionization electron tube G3 of the receiving channel responsive to recurrent impulses of direct current is preceded by a stage of amplification including a high vacuum electron tube 6Q7 of the indirect heater type and having two diode plates 189 and 190. The grid circuit of tube G3 is coupled with the plate circuit of the preceding amplifier tube 6Q7 by a circuit including resistors 161 and 162 and a condenser 163. A resistor 191 is interposed in the grid circuit of tube G3 between the resistor 162 and the terminal N32. The grid circuit for tube 6Q7 is connected directly with the inductor windings 25 and 26, a resistor 192 being interposed in the circuit adjacent the terminal N32 as is apparent from Fig. 3. The resistors 192 and 191 provide desirable normal grid bias voltages for tubes G3 and 6Q7, respectively.

The receiving channel of Fig. 3 responsive to coded alternating current includes transformer T13, tube 25L6 and master relay MR the same as in Fig. 2, the windings of transformer T13 and condensers 174 and 184 forming a filter interposed between the grid of tube 25L6 and the inductor windings 25 and 26.

The master relays MR and MR1 control current impulses supplied to the frequency decoding unit TFD by controlling the supply of direct current to the primary winding 168 of transformer T11 in the same manner as in Fig. 2 except in Fig. 3 the transformer T15, rectifier 187, relay R6 and resistor 197 are omitted.

In Fig. 3, the means for desensitizing the receiving channel including tube 25L6 so that it is not responsive to direct current impulses consists of the filter including condensers 174 and 184 and transformer T13 the same as in Fig. 2. In Fig. 3, the means for automatically desensitizing the receiving channel including tube G3 when coded alternating current is picked up from the track circuits includes two condensers 193 and 194. Condenser 193 is connected between a point P in the supply circuit for transformer T11 and the resistor 191 of the grid circuit of tube G3, and condenser 194 is connected between a point Q in the supply circuit for transformer T11 and the resistor 192 of the grid circuit of tube 6Q7. Also one side of condenser 193 is connected with the diode plate 190 of tube 6Q7 over wire 199 and one side of condenser 194 is connected with diode plate 189 over wire 200. Point P is located in the supply circuit between the contact member 182 of relay MR and contact member 169 of relay MR1, and point P is located in the supply circuit between the contact member 183 of relay MR and the mid terminal of winding 168 of transformer T11.

When the train on which the apparatus of Fig. 3 is mounted operates over track circuits supplied with code impulses of direct current of different code rates as provided by the trackway apparatus of Fig. 1, the receiving channel including tube G3 and relay MR1 is responsive and operates in the same manner as described in detail in Fig. 2 except that the electromotive forces in-

duced in windings 25 and 26 are first amplified at tube 6Q7.

When the train is operated over track circuits to which coded alternating current of different code rates is supplied, say by trackway apparatus 5 shown in the aforementioned Patent No. 1,773,515, the receiving channel including tube 25L6 and master relay MR is responsive to control the cab signal CS1 the same as in Fig. 2.

When master relay MR of Fig. 3 is not operating, the voltage appearing between points P and Q is essentially a direct current voltage whether master relay MR1 is operating or not. When relay MR is operating in response to code impulses of alternating current, the current supplied to winding 168 is periodically reversed and surges of alternating current voltages appear between points P and Q whenever relay MR operates to interrupt the circuit. The alternating voltages appearing between points P and Q are supplied through condensers 193 and 194 to the diode plates 189 and 190 of tube 6Q7 where such voltages are rectified and applied as unidirectional voltages across resistors 191 and 192. Such rectified unidirectional voltages create voltages which are added to the normal negative bias voltages of tubes 6Q7 and G3. The parts are so proportioned that the grid bias voltages applied to tubes 6Q7 and G3 are correct only when no rectified current is applied to resistors 191 and 192. The voltages created by the rectified current flowing in these resistors when added to the normal bias voltages causes tubes 6Q7 and G3 to be so highly negative that they no longer function. Consequently, when the train is operated over territory in which the track circuits are supplied with coded alternating current, the receiving channel normally responsive to direct current impulses is desensitized, and when the train is operating over territory using track circuits in which impulses of direct current are supplied, the receiving channel normally responsive to alternating current is unaffected due to the tuning of the filter included in that receiving channel.

In Fig. 4, the train carried apparatus is the same as in Fig. 3 except for the means used to desensitize the tubes 6Q7 and G3. In Fig. 4, the diode plates 189 and 190 of tube 6Q7 are connected in a full wave rectifier circuit made up of condensers 193 and 194 and an additional condenser 201, together with resistors 202, 203 and 204. Alternating surges of voltages appearing at points P and Q when master relay MR is operating are rectified by the diode plates 189 and 190 and are effective to charge the condenser 201. The voltage across condenser 201 when thus charged adds to the normal bias voltages of tubes 6Q7 and G3, and these tubes are provided with a bias of such negative potential that they can no longer operate.

It is clear, therefore, that when a train on which the apparatus of Fig. 4 is mounted operates over territory using track circuits supplied with coded alternating current, the receiving channel including tube 25L6 and relay MR is responsive to control the cab signal CS1. When the train operates over territory using track circuits supplied with coded direct current, the receiving channel including tube G3 and relay MR1 is responsive to control the cab signal CS1, the operation being substantially the same as described in connection with the apparatus of Fig. 2.

It is to be understood, of course, that the train carried apparatus of any of the several forms of apparatus embodying my invention can include

circuits for controlling the air brake and power equipment according to any of the well-known arrangements, if desired.

Although I have herein shown and described 5 only certain forms of apparatus embodying my invention, it is understood that various changes and modifications may be made therein within the scope of the appended claims without departing from the spirit and scope of my invention.

10 Having thus described my invention, what I claim is:

1. Railway traffic controlling apparatus for use either with a first territory provided with track circuits supplied with alternating current of a 15 given frequency coded at different code rates according to different traffic conditions or with a second territory provided with track circuits supplied with direct current coded at said different code rates according to said different traffic conditions comprising, a train, a receiving circuit mounted on the train for receiving energy from such track circuits, a first train carried receiving channel including a first code following relay normally effective to operate said first relay 20 when energy is periodically applied to the input terminals of that channel, a second train carried receiving channel including a second code following relay normally effective to operate said second relay when energy is periodically applied 25 to the input terminals of that channel, means including a filter tuned to resonance at said given frequency of said alternating current to connect said receiving circuit with the input terminals of said first channel to operate said first relay only 30 when the train traverses said first territory, means to connect said receiving circuit with the input terminals of said second channel, means including a contact of said first relay to desensitize said second channel when said first relay 35 is operated to permit operation of said second relay only when said train traverses said second territory, a decoding unit selectively responsive to current impulses corresponding to said different code rates, circuit means including a contact of each of said relays to supply such current 40 impulses to said decoding unit when either of said relays is operated, and a signal having a different indication for each of said different traffic conditions controlled by said decoding 45 unit.

50 2. Railway traffic controlling apparatus for use either with a first territory provided with track circuits supplied with alternating current of a given frequency coded at different code rates 55 according to different traffic conditions or with a second territory provided with track circuits supplied with direct current coded at said different code rates according to said different traffic conditions comprising, a train, a receiving circuit mounted on the train for receiving energy from such track circuits, a first and a second train carried receiving channel the input terminals of which are connected in parallel to said receiving circuit; each of said receiving 60 channels including an electron tube, a code following relay and a current source and each channel normally effective to cause operation of the associated relay when energy is periodically applied to the input terminals of that channel, 65 a filter tuned to resonance at said given frequency of said alternating current interposed in the grid circuit to the tube of said first channel to permit operation of the relay of said first channel only when the train traverses said first territory, means including a contact of the relay 70

of said first channel to desensitize the tube of said second channel when the relay of the first channel is operated to permit operation of the relay of the second channel only when the train traverses said second territory, a decoding unit 5 selectively responsive to current impulses corresponding to said different code rates, and circuit means including a contact of each of said relays to control said decoding unit.

3. Railway traffic controlling apparatus for use 10 either with a first territory provided with track circuits supplied with alternating current of a given frequency coded at different code rates according to different traffic conditions or with a second territory provided with track circuits supplied with direct current coded at said different code rates according to said different traffic conditions comprising, a train, a receiving circuit mounted on the train for receiving energy from such track circuits, a first and a second train 15 carried receiving channel; said first channel including a first electron tube, a first relay and a current source; said first tube having its control element connected with said receiving circuit and its anode and cathode connected with said current source through a winding of said first relay, said first channel normally effective to cause said first relay to be operated when energy is periodically applied to the control element of said first tube; said second receiving 20 channel including a second electron tube, a second relay and a current source; said second tube having its control element connected with said receiving circuit and its anode and cathode connected with the associated current source through a winding of said second relay, said second channel effective to cause said second relay to be operated when energy is periodically applied to the control element of said second tube, a filter tuned to resonance at said given 25 frequency interposed in the connection of the receiving circuit with the control element of said first tube to operate said first relay when the train traverses said first territory, means including a contact of said first relay to desensitize said second tube when said first relay is operated to 30 permit operation of said second relay only when the train traverses said second territory, a decoding unit selectively responsive to current impulses corresponding to said different code rates, 35 and circuit means including a contact of each of said relays to control said decoding unit.

4. Railway traffic controlling apparatus for use 40 either with a first territory provided with track circuits supplied with alternating current of a given frequency coded at different code rates according to different traffic conditions or with a second territory provided with track circuits supplied with direct current coded at said different code rates according to said different traffic 45 conditions comprising, a train, a receiving circuit mounted on the train for receiving energy from such track circuits, a first and a second train carried receiving channel; said first receiving channel including a high vacuum electron tube, a first relay and a current source; said electron tube having a grid circuit coupled with said receiving circuit and an anode circuit including a winding of said relay and said current source, said first channel normally effective to 50 operate said relay when alternating current is periodically supplied to said grid circuit; said second receiving channel including a controlled ionization electron tube, a second relay, a reactance device and a current source; said con- 55

trolled ionization tube having a control element coupled with said receiving circuit and an anode circuit including a winding of said second relay and the associated current source, said reactance device connected with the anode and cathode of the controlled ionization tube to store energy in the device when the tube is nonconductive and give up such stored energy to deionize the tube when the tube is made conductive, said second channel normally effective to operate said second relay when energy of a preselected polarity is applied to the control element of said controlled ionization tube, a filter tuned to resonance at said given frequency interposed in the coupling between the grid of said high vacuum tube and the receiving circuit to permit operation of said first relay only when the train traverses said first territory, means including a contact of said first relay to desensitize said controlled ionization tube when said first relay is operated to permit operation of said second relay only when the train traverses said second territory, a decoding unit selectively responsive to current impulses corresponding to said different code rates, and circuit means including a contact of each of said relays to control said decoding unit.

5. Railway traffic controlling apparatus for use either with a first track circuit supplied at times with coded alternating current of a given frequency or with a second track circuit supplied at times with coded direct current of a given polarity comprising, a train, a receiving circuit mounted on the train for receiving energy from such track circuits, a first and a second train carried receiving apparatus; said first receiving apparatus including a first electron tube, a first relay and a current source; said first tube having its control element coupled with said receiving circuit and its anode and cathode connected with said current source through said first relay and said first apparatus arranged to cause operation of the first relay when an electromotive force is periodically applied to the control element of said first tube; said second receiving apparatus including a second electron tube, a second relay and a current source; said second tube having its control element coupled with said receiving circuit and its anode and cathode connected with the associated current source through said second relay and said second apparatus arranged to cause operation of said second relay when an electromotive force of a selected polarity is periodically applied to the control element of said second tube, a filter tuned sharply to pass only alternating current of said given frequency interposed between the control element of said first tube and said receiving circuit to permit operation of said first relay only when the train occupies said first track circuit, means including a contact of said first relay to desensitize said second receiving apparatus when said first relay is operated to permit operation of said second relay only when the train occupies said second track circuit, and a signaling circuit including a contact of each of said relays effectively controlled when either relay is operated.

6. Railway traffic controlling apparatus for use either with a first track circuit supplied at times with coded alternating current of a given frequency or with a second track circuit supplied at times with coded direct current of a given polarity comprising, a train, a receiving circuit mounted on the train for receiving energy from such track circuits, a first and a second train carried receiving apparatus; said first receiving

apparatus including a high vacuum electron tube, a first relay and a current source; an anode circuit including said first relay and said current source for said tube, a grid circuit for said tube coupled with said receiving circuit to cause operation of said first relay when energy is periodically applied to the grid from said receiving circuit; said second receiving apparatus including a controlled ionization electron tube, a second relay, a condenser and a current source; an anode circuit including said second relay and said last mentioned current source for said controlled ionization tube normally ineffective to ionize the tube, a circuit including said condenser connected with the anode and cathode of the controlled ionization tube to deionize the tube when the tube is conductive, a grid circuit for said controlled ionization tube coupled with the receiving circuit to ionize that tube and operate said second relay when energy of said given polarity is received by said receiving circuit, a filter tuned to pass only current of said given frequency interposed in the grid circuit of said high vacuum tube to operate said first receiving apparatus only when the train occupies said first track circuit, means including a contact of said first relay to desensitize said controlled ionization tube when said first relay is operated for operating said second receiving apparatus only when the train occupies said second track circuit, and a signaling circuit including a contact of each of said relays effectively controlled when either relay is operated.

7. Railway traffic controlling apparatus for use either with a first track circuit supplied at times with coded alternating current of a given frequency or with a second track circuit supplied at times with coded direct current of a given polarity comprising, a train, a receiving circuit mounted on the train for receiving energy from such track circuits, a first and a second train carried receiving apparatus; said first receiving apparatus including a high vacuum electron tube, a first relay and a current source; an anode circuit including said first relay and said current source for said tube, a grid circuit for said tube coupled with said receiving circuit to cause operation of said first relay when energy is periodically applied to the grid from said receiving circuit; said second receiving apparatus including a controlled ionization electron tube, a second relay, a condenser and a current source; an anode circuit including said second relay and said last mentioned current source for said controlled ionization tube normally ineffective to ionize the tube, a circuit including said condenser connected with the anode and cathode of the controlled ionization tube to deionize the tube when the tube is conductive, a grid circuit for said controlled ionization tube coupled with the receiving circuit to ionize that tube and operate said second relay when energy of said given polarity is received by said receiving circuit, a filter tuned to resonance at said given frequency interposed in the grid circuit of said high vacuum tube to cause operation of said first relay only when the train occupies said first track circuit, a signaling circuit including a contact of each of said relays effectively controlled when either of said relays is operated, another relay controlled by said signaling circuit and effectively energized only when said first relay is operated, and means including a back contact of said other relay to remove the current source of the second receiving apparatus from the anode circuit of said controlled ioniza-

- tion tube to permit operation of said second relay only when the train occupies said second track circuit.
8. Railway traffic controlling apparatus for use either with a first track circuit supplied at times with coded alternating current of a given frequency or with a second track circuit supplied at times with coded direct current of a given polarity comprising, a train, a receiving circuit mounted on the train for receiving energy from such track circuits, a first and a second train carried receiving apparatus; said first receiving apparatus including a high vacuum electron tube, a first relay and a current source; an anode circuit including said first relay and said current source for said tube, a grid circuit for said tube coupled with said receiving circuit to cause operation of said first relay when energy is periodically applied to the grid from said receiving circuit; said second receiving apparatus including a controlled ionization electron tube, a second relay, a condenser and a current source; an anode circuit including said second relay and said last mentioned current source for said controlled ionization tube normally ineffective to ionize the tube, a circuit including said condenser connected with the anode and cathode of the controlled ionization tube to deionize the tube when the tube is conductive, a grid circuit for said controlled ionization tube coupled with the receiving circuit to ionize that tube and operate said second relay when energy of said given polarity is received by said receiving circuit, a filter tuned to resonance at said given frequency interposed in the grid circuit of said high vacuum tube to cause operation of said first relay only when the train occupies said first track circuit, a signaling circuit including a contact of each of said relays effectively controlled when either of said relays is operated, and biasing means including another condenser connected with the grid circuit of said controlled ionization tube and with said signaling circuit to create a negative grid bias for that tube when said first relay is operated whereby said second receiving apparatus is effective to operate said second relay only when the train occupies said second track circuit.
9. Railway traffic controlling apparatus for use either with a first track circuit supplied at times with coded alternating current of a given frequency or with a second track circuit supplied at times with coded direct current of a given polarity comprising, a train, a receiving circuit mounted on the train for receiving energy from such track circuits, a first and a second train carried receiving apparatus; said first receiving apparatus including a high vacuum electron tube, a first relay and a current source; an anode circuit including said first relay and said current source for said tube, a grid circuit for said tube coupled with said receiving circuit to cause operation of said first relay when energy of said given frequency is periodically applied to said grid from said receiving circuit; said second receiving apparatus including a controlled ionization electron tube, a second relay, a condenser and a current source; an anode circuit including said second relay and said last mentioned current source for said controlled ionization tube normally ineffective to ionize the tube, a circuit including said condenser connected with the anode and cathode of the controlled ionization tube to deionize the tube when the tube is conductive, a grid circuit for said controlled ionization tube coupled with the receiving circuit to ionize that tube and operate said second relay when energy of said given polarity is received by said receiving circuit, a filter tuned to resonance at said given frequency interposed in the grid circuit of said high vacuum tube to cause operation of said first relay only when the train occupies said first track circuit, a signaling circuit including a contact of each of said relays effectively controlled when either of said relays is operated, a biasing unit including a condenser and a resistor in multiple interposed in the grid circuit of said controlled ionization tube to establish a normal grid bias for that tube, additional biasing means including another condenser and a rectifier connected with said biasing unit and with said signaling circuit to modify the grid bias of said controlled ionization tube when said first relay is operated to permit operation of said second relay only when said train occupies said second track circuit.
